UNITED STATES PATENT OFFICE

SANFORD L. CLUETT, OF TROY, NEW YORK

CLOTH-FINISHING

Application filed February 19, 1931. Serial No. 516,973.

In an application for United States Letters Patent, filed by me on April 18, 1930, Serial No. 445,300, I describe and claim a method of effecting preshrinkage in textile fabrics which, briefly stated, comprises affixing by pressure a textile web in a moistened and therefore plastic condition, at all parts of its surface to a contractile support, then causing the support to contract while the web is held fixed to it, so that the web also contracts in area, and then, as by heat and drying, setting the web in its thus altered state. The superficial contraction of the web is produced by pressure exerted in directions parallel to its surfaces; since by reason of the confinement of the web by the pressure maintained on its entire surface it can not wrinkle as a web or sheet in response to the contractile force exerted on it, the response to that force is by the component yarn systems within the web (one or both) of which the web is composed, which assume a more pronounced undulation or crinkle, contracting the web without wrinkling its surface. This may, for the sake of brevity, be termed shrinkage by compression.

Apparatus by which shrinkage by compression is effected is exemplified by one endless band of such thickness and structure that on being flexed during its movement successively in one direction and then in the reverse, that side of the band which is first convex and then concave lengthens and then shortens, so that a moist web of cloth laid upon and attached by pressure to, this convex sector partakes of the contraction of the band surface when the latter passes into the concave sector, when also the confining pressure continues to be exerted on the web. In its passage through the concave sector, the web responds to the contractile force by the crinkling of the warp yarns.

The present invention aims to provide novel and improved apparatus for cloth shrinkage by compression; particularly to provide apparatus utilizing many parts of commercial cloth drying or finishing machines, significantly rearranged and modified with alteration of function so as to produce this type of shrinkage.

A further object of the invention is to provide an improved organization of instrumentalities capable of confining the cloth web against the convex surface of a moving band, and without any substantial release of this confinement, so altering the curvature of the band as to produce shrinkage by compression. Various features of novelty and improvement in this organization of instrumentalities and in the machine as a whole will be apparent from this specification and its drawings, wherein an illustrative embodiment of my invention is explained by way of example.

In the drawings:

Fig. 1 is a diagrammatic side elevation of a cloth-shrinking machine embodying features of the present invention;

Fig. 2 is a vertical section on the line 2—2 of Fig. 1;

Fig. 3 is a plan of the parts shown in Fig. 2;

Fig. 4 is a vertical section on the line 4—4 of Fig. 2; and

Fig. 5 is a view similar to Fig. 4, but showing certain ironing instrumentalities of the machine in an inactive position.

The compressive shrinking machine of the present invention is suited to form part of the general organization of cooperative cloth-finishing devices described in my co-pending application serially numbered 516,972, filed Feb. 19, 1931.

Fig. 1 shows how, in obtaining accurate two-dimensional preshrinkage, as explained in that application, a textile web W may be conducted from a tentering machine T, through rolls R, R, past water moistening devices M, M, and smoothing and spreading bars or rolls G¹, G², G³ and G⁴ to a machine of the present invention operating on the principle of compressive shrinkage.

This machine of the present invention for effecting shrinkage by compression, includes an endless flexible band F, for example of felt about $\frac{1}{4}$ th of an inch thick, which is carried over the convex surface of a member R¹ defining a part of the path of travel of the band. This member R¹ preferably is a rotatable roll. The band F passes therefrom

on to the surface of a second member D which moves past the convex surface of this first member R¹. Preferably this second member D is a large rotatably driven cloth-drying drum, provided with means for internal heating (not shown); the band F may then pass around the major portion of the drum to and over a series of rolls R², R², and from thence return to member R¹. Any one of the several rolls R² may be adjusted to impart a sufficient tension to the band F to enable the band to be driven by the drum D. Better operation of the device is secured with less tension on the band F if a roll, indicated at R⁵, is provided by pressing the band F toward the drum D shortly after the band leaves roll R¹; suitable springs, not shown, are preferably provided for urging the roll R⁵ against the band at this point.

20 The textile web W to be subjected to warpwise compressive shrinking is received in a moist plastic state by the convex surface of the band F passing over the member R¹. From thence the web W accompanies the band F as the latter is transferred to the drum D. After passing around the drum D with the band F, the web W diverges from the band as diagrammatically indicated in Fig. 1. Wide webs of a yard and more in width can be successfully handled.

25 Means is provided for causing the roll R¹ and drum D to nip the band F and its associated textile web at the point where the band and web are transferred from the roll to the drum. Preferably as shown in Figs. 2 and 4, the roll R¹ is mounted at opposite ends in frames A which are pivotally mounted at A¹ to a stationary upright G, the pivot point A¹ being in the present instance above the axis of roll R¹ and offset therefrom toward the drum D, so that the pull of the band F will draw the roll R¹ toward the drum D. This produces a decided compressive nip, at about the point marked N (Fig. 4) upon the band F, where in passing from member R¹ to member D its flexure is reversed. To provide for vertical adjustment of the roll R¹, a journal J at each of its ends is preferably embraced by opposed cupped bearing blocks 30 K and K¹ which are vertically adjustable by means of upper and lower adjusting screws L and L¹, turning in bosses X and X¹ on the frame A. Preferably, means is provided for adjusting the degree of compressive nipping 35 of the band and web between the roll R¹ and drum D; a preferred form of such means may include a pin V carried by the pivoted roll-carrying frame A and adjustably pressed by a spring V¹ against the upright G, thus 40 adjustably limiting and cushioning the pivotal movement of the frame A and roll R¹ toward the drum D. For adjustably limiting outward movement of the frame A and roll R¹ away from the drum D, a sleeve T³ pivotally secured at T⁴ to the frame A, may take

against a spring T⁶ adjustably confined by a nut T² on a bolt T⁵, which is pivoted to the upright G at T¹.

Cloth passing over the convex surface of the band F on roll R¹ and then onto drum D would in the absence of precautionary measures, tend to wrinkle at a point just before the cloth is nipped between the roll and drum D. Wrinkling of the cloth at this point would be highly undesirable since the wrinkles would be ironed into the finished cloth. Attempts to prevent such wrinkling by merely applying a very high warpwise tension to the cloth would tend to cause imperfect feeding of the cloth with local slipping of the cloth with respect to the band and drum at various points across the considerable width of the cloth, and hence loss of perfect weft-alignment and failure to obtain uniform shrinkage of each part of the cloth. Another disadvantageous result of the mere employment of a high degree of warpwise tension in attempts to prevent wrinkling at this point is excessive straightening of the warps, tending to counteract, or even exceeding, the subsequently imposed warpwise shrinkage, and also causing the wefts of the plastic web to take up or crinkle more than is usually necessary or desirable. In order satisfactorily to prevent such tendency of the cloth to wrinkle, and incidentally to increase the warpwise shrinking capacity of the machine, and to ensure uniformity of feeding of the web, means is provided for confining the web W against the band F until the web and band substantially reach the point N at which they are nipped between the roll R¹ and drum D. Such means preferably takes the form of a plurality of ironing blocks I disposed closely side by side across the width of the web W (Fig. 3) and each conforming (Fig. 4) to the convex surface of the web W passing the member R¹. Preferably these ironing blocks extend as near as possible to the nip point N, conforming to the curvature of the web immediately before the web is nipped as described above. With this arrangement, the web is transferred from pressure-confinement against the band F to similar confinement against the moving surface of the drum D with no substantial release from pressure against the band. The moisture contained in the web (for example 10% by weight of water) as a consequence of previous moistening by the water spraying devices M, enables the web to be firmly affixed or attached to the band F prior to flexure of the band in passing onto the drum D.

The ironing blocks I preferably contain electric heating elements Y, which may be of conventional form; the ironing blocks thus heated affix the plastic web W to the band F both by heat and pressure. The heating of the ironing blocks I is of particular utility

also in preventing the accumulation of starch or the like from the web being ironed, and in making the moistened fabric or web slide over the surface of the block with little or no friction.

Preferably the several blocks I rest independently on the cloth, thus ensuring that all parts of the width of cloth are firmly confined against and attached to the band F, regardless of slight flexure of the roll R¹. Each ironing block I, while having freedom of motion normal to the web W, may be prevented from being carried by the web too tightly against the drum D or from being wedged unduly between the drum D and roll R¹, by the provision of an adjustable abutment in the form of a screw bolt O¹ affixed in the lower flange of a channel iron O and taking against the upper surface of a lip I¹ on the ironing block. Each ironing block I or equivalent web-confining member may if desired be yieldingly urged against the web W, not only by gravity but also by spring action; as shown in Fig. 4, a spring V¹ attached to the channel iron O, and to the lip I¹ of the ironing block, may urge the block against the web, about the bolt O¹ as a fulcrum.

The machine is adapted in its operation to produce preshrinkage by compression, as follows:

The web W is in a moist condition when it enters between the band F and blocks I, so that its component yarns are soft and their fibre structure capable of internal movement. As the band F passes the point N, the web is transferred from pressure-confinement against the band F by the blocks I to similar confinement between the band and the surface of the drum D, with no appreciable, or more than an instant's release from pressure against the band, so that the reversal of curvature of the band, and the consequent shortening of its web-carrying surface, is accompanied by a corresponding shortening of the moist web, of which the yarn components (warp in this case) produces take up or shrinkage by undulation or crinkle. The shrinkage produced in the web is then set by the heating and drying on the hot drum D, and the web drawn from the band to be rolled or web folded. If a given length of the convex surface of the band F, upon the roll R¹ be represented by L, and this, upon passing to the drum D contracts to a length L¹, the linear contraction is expressible by L-L¹, and the percentage of shrinkage by

$$\frac{L-L^1}{L}.$$

This represents the maximum compression shrinkage producible in a web by the means above described.

The extent of contraction (L-L¹) of the

band F in passing from the roll R¹ to the drum D is an inverse function of the radius of roll R¹ and is a direct function of the thickness of the band F; and the extent of shrinkage in a web W may be regulated by a suitable proportioning of these values.

Whenever the progress of the cloth web under the ironing blocks I is interrupted, it is desirable to lift and hold the blocks I out of contact with the web W, thus to prevent scorching of the web. Suitable means for accomplishing these functions preferably includes a pair of brackets E at opposite ends of, and affixed to, the channel O, each of these brackets E being pivotally mounted at E¹ to a curved plate A³ which is supported by the pivoted roll-carrying frame A. The two brackets E thus movably support the channel O, forming together therewith a yoke which can be swung from the position of Fig. 4 to the position of Fig. 5; an extension E² of each bracket E in this position strikes a stop E⁴ and checks further movement of the brackets E and channel O. The individual ironing blocks I may be caused to move as a unit with this yoke by suitable connections thereto, thus being removed from contact with the cloth web, as shown in Fig. 5. Preferably such connections provide freedom of movement of the individual blocks when the yoke and blocks are in normal operative position, as in Fig. 4. As shown in Figs. 3 and 4, a rod P extending across the group of blocks I is affixed at intervals to the channel I by brackets P¹ fast thereto. Each ironing block I then carries one or more hooks I⁵ disposed to engage the rod P of the above described yoke construction when the latter is swung to the right, but free from the rod P when the blocks I are in their normal operating position. In order to hold the yoke, including brackets E, channel O and rod P, free from the blocks I during operation of the blocks, suitable swinging hooks P² may be provided on each plate A³, adapted to latch over the rod P.

Preferably electrical connections to the heating elements Y of each ironing block I are so arranged as to permit ready detachment of any of the individual blocks. As shown in Fig. 4, electrical wires Q connected to the several heating elements Y of a block through holes in the top of the block, terminate in a detachable plug Q¹. A smaller channel member O⁴ within the flanges of channel O carries on the outer face of its web suitable electrical outlets Q² to which the plugs Q¹ may be detachably connected. The necessary wires leading from a source of energy to the outlets Q² are preferably enclosed in the space between the channels O and O⁴.

It should be understood that the present disclosure is for the purpose of illustration only and that this invention includes all

modifications and equivalents which fall within the scope of the appended claims.

I claim:

1. A cloth-finishing machine adapted to shrink cloth in length, said machine comprising a flexible band, a member having a convex surface defining a path of travel for said band, means for supplying a textile web to the convex surface of the band on said member, a second member having a surface movable past said first-named member and defining a subsequent path of travel for the band, said first and second members being disposed to cooperate in nipping the web and band at the point where the band passes from one to the other of said members, in combination with means for compressively confining the web against said band by pressure maintained thereon substantially up to the point at which the web and band are nipped by said first and second members.

2. A cloth-finishing machine adapted to shrink cloth in length, said machine comprising a flexible band, a member having a convex surface defining a path of travel for said band, means for supplying a textile web to the convex surface of the band on said member, a second member having a surface movable past said first-named member and defining a subsequent path of travel for the band, said first and second members being disposed to cooperate in nipping the web and band at the point where the band passes from one to the other of said members, in combination with a pressure element conforming to the curvature of the web immediately before the web is nipped by said members, said pressure element being arranged to press the web against said band until the web and band are thus nipped, whereby the web is transferred from pressure-confinement against the band to similar confinement against the movable surface of said second member with no substantial interval of release from pressure against the band.

3. A cloth-finishing machine adapted to shrink cloth in length, said machine having therein a roll, an endless band passing thereover, a rotatable drum receiving the band from said roll, the roll and the drum being arranged to nip the band between them as the band passes from one to the other with consequent reversal of curvature, and an ironing block conforming to the convexity of the band on the roll and extending substantially to the point at which the cloth and band are nipped by the roll and drum for affixing a textile web to the surface of said band.

4. A cloth-finishing machine adapted to shrink cloth in length, said machine having therein a roll, an endless band passing thereover, a rotatable drum receiving the band from said roll, the roll and the drum being arranged to nip the band between them as the band passes from one to the other with

consequent reversal of curvature, an ironing block conforming to the convexity of the band on the roll and extending substantially to the point at which the cloth and band are nipped by the roll and drum for affixing a textile web to the surface of said band and means for heating said ironing block.

5. A cloth-finishing machine comprising a flexible band, a member having a convex surface defining a path of travel for said band, means for supplying a textile web to the convex surface of the band on said member, a second member having a surface movable past said first-named member and defining a subsequent path of travel for the band, said first and second members being disposed to cooperate in nipping the web and band at the point where the band passes from one to the other of said members, in combination with a plurality of pressure elements each conforming to the curvature of the web immediately before the web is nipped by said members, said pressure elements lying side by side in close relationship and extending as a group across the width of the web of cloth being treated, in position to press the web and band against said convex first-named member close to the movable surface of said second-named member.

6. A cloth-finishing machine adapted to shrink cloth in length, said machine having therein a roll, an endless band passing thereover, a rotatable drum receiving the band from said roll, the roll and the drum being arranged to nip the band between them as the band passes from one to the other with consequent reversal of curvature, and a plurality of ironing blocks each conforming to the convexity of the band on the roll, and extending substantially to the point at which the cloth and band are nipped by the roll and drum said ironing blocks resting independently upon a web of cloth on the web and extending as a group axially of the said roll.

7. A cloth-finishing machine having therein an endless band adapted to receive a textile web to be treated, a member having a convex surface defining part of a path of travel of said band, a second member having a surface movable past said first-named member and defining a subsequent part of the path of travel of said band, said first and second members being disposed with respect to each other to cooperate in nipping the band and a web thereon at the point where the band passes from one to the other of said members, a plurality of ironing blocks conforming to the curvature of the web on the band at said convex surface of the first-named member, said ironing blocks extending as a group across the width of the textile web being treated, means for heating the several ironing blocks, and means for supporting the ironing blocks out of contact with the web,

- thereby to prevent scorching of the web when the progress of the web is stopped.
8. A cloth-finishing machine having therein an endless band adapted to receive thereon a textile web to be treated, a member having a convex surface defining a part of a path of travel of said band, a second member having a surface movable past said first-named member and defining a subsequent part of the path of travel of said band, said first and second members being disposed with respect to each other to nip the band and a web thereon at the point where the band passes from one to the other of said members, an ironing block conforming to the curvature of the said textile web closely adjacent to the point at which said web is nipped between said members, and means for preventing the block from being unduly nipped between said members with the web, while permitting the said block to float upon the surface of the moving web as the latter passes over the said first member.
9. A cloth-finishing machine having therein an endless band adapted to receive thereon a textile web to be treated, a member having a convex surface defining a part of a path of travel of said band, a second member having a surface movable past said first-named member and defining a subsequent part of the path of travel of said band, said first and second members being disposed with respect to each other to nip the band and a web thereon at the point where the band passes from one to the other of said members, an ironing block conforming to the curvature of the said textile web closely adjacent to the point at which said web is nipped between said members, an abutment positioned to check movement of the ironing block in the direction of progress of the band toward the point where the band is nipped, while permitting the block freedom of motion in a direction normal to the textile web, and means for yieldingly urging the ironing block toward the web.
- 45 10. A cloth-finishing machine adapted to shrink cloth in length, said machine having therein an endless band adapted to receive thereon a textile web to be treated, a member having a convex surface defining a part of a path of travel of said band, a second member having a surface movable past said first-named member and defining a subsequent part of the path of travel of said band, said first and second members being disposed with respect to each other to nip the band and a web thereon at the point where the band passes from one to the other of said members, a plurality of ironing blocks conforming to the curved surface of the textile web where the latter moves over the convex member, said blocks being mounted yieldingly to bear against the web at this point to affix the web to the band, and means for removing the several blocks as a unit from contact with the web.
11. A cloth-finishing machine having therein an endless band adapted to receive thereon a textile web to be treated, a member having a convex surface defining a part of a path of travel of said band, a second member having a surface movable past said first-named member and defining a subsequent part of the path of travel of said band, said first and second members being disposed with respect to each other to nip the band and a web thereon at the point where the band passes from one to the other of said members, a plurality of ironing blocks conforming to the curved surface of the textile web where the latter moves over the convex member, said blocks being mounted yieldingly to bear against the web at this point to affix the web to the band, a yoke extending across the group of ironing blocks, said yoke being movable toward and away from the normal position of said blocks, and connections between the several blocks and said yoke whereby the blocks may be removed from contact with the web by movement of the yoke, said connections providing freedom of motion of the individual blocks with respect to the yoke when the yoke is moved toward the normal position of the ironing blocks.
12. A cloth-finishing machine adapted to shrink cloth in length, said machine comprising a flexible band adapted to receive thereon a moist plastic web to be treated, a member having a convex surface defining a path of travel for said band, a second member having a surface movable past said first-named member and defining a subsequent path of travel for the band, said first and second members being disposed to cooperate in nipping the web and band at the point where the band passes from one to the other of said members, in combination with means, operable with respect to the web in advance of and immediately adjacent to the point at which the web is nipped by the said two members, acting to press the web into close contact with the band.
- Signed by me at Troy, N. Y., U. S. A., this 14 day of Feb., 1931.
- SANFORD L. CLUETT.
